[57] ABSTRACT

A compressor pump or the like including a cylinder and piston assembly and a pressure chamber, the cylinder having an inlet and having an outlet in communication with the pressure chamber, the piston having a working face in the cylinder and having a pressure face exteriorly of the cylinder, cam means engaging the pressure face of the piston whereby relative rotation between the cylinder and piston as a unit and the cam plate causes reciprocation of the piston and compression of gases in the cylinder and also in the pressure chamber, the cam plate, during the compression stroke of the piston, exposing the pressure face of the piston to pressure chamber pressures to provide added power in the compression stroke of the piston, the pressure face of the piston being relieved of pressure chamber pressures during the intake stroke of the piston.

COMPRESSOR PUMP

This invention relates to a compressor pump or the like.

Conventional compressors for air and other gases generally are of a reciprocating piston type, the piston having an intake stroke in which air is drawn into the cylinder in which the piston works, and a compression stroke in which the piston moves into the cylinder, compressing the air and forcing the compressed air through an outlet port and into an air hose or a storage reservoir.

The compression stroke of the piston in the conventional compressor must be accomplished with sufficient power to overcome the buildup pressure in a hose or in a storage reservoir. The result is that not only must the piston be sufficiently powered to compress gas in the cylinder but to also overcome the storage pressure.

It is an object of the present invention to provide a compressor wherein the pressure in a pressure chamber or reservoir is utilized to provide pressure against the piston to assist a driving element, such as a cam, in forcing the piston into the cylinder during the compression stroke. The result is that the cam or other piston driving element is required to do much less work during the compression stroke. This of course results in the need for the application of less power since the power device is assisted by the stored up energy in the pressure chamber and also, it results in much smoother operation of the compressor. This latter feature is quite important in installations, such as the air conditioning systems of motor vehicles, wherein present types of compressors not only utilize a considerable amount of the horsepower of the vehicle engine but cause an appreciable amount of vibration in the vehicle.

A further object is to provide a compressor wherein piston movement is accomplished with a cam plate in the nature of a wobble plate, the piston having an end extending from the cylinder and connected to the cam plate by means maintaining the piston and cam plate in engagement but providing sliding movement between them upon relative rotation between the cam plate and the piston.

A further object is to provide a cam plate disposed obliquely to the longitudinal axis of the piston, the cam plate and the exposed end of the piston being located in a pressure chamber and the cam plate having a cut-away portion about half of its surface so that the end of the piston engaging the cam plate will be exposed to pressure chamber pressures, this exposure occurring during the compression stroke of the piston.

Another object is to provide a piston having a working face in the cylinder and a pressure face exteriorly of the cylinder, the pressure face being flat and on a plane oblique to the longitudinal axis of the piston and coincident with the plane of the cam plate so that the piston and cam plate are in flat face-to-face engagement sealing out pressures from the pressure chamber during the intake stroke of the piston, the cam and piston faces providing free relative sliding movement much in the manner of a set of Johansson gages.

The above and other objects will more fully appear from the following description in connection with the accompanying drawings:

FIG. 1 is a side elevational view of an embodiment of the invention;

FIG. 2 is an enlarged vertical sectional view through the device of FIG. 1;

FIG. 3 is a perspective view of the pistons and cam plate;

FIG. 4 is a diagrammatic view partially in section illustrating one cycle of piston movement;

FIG. 5 is a plan view of the cam plate.

The device includes a housing 6 having a removable cover 8 which supports a sleeve 10 having an air inlet 12, the sleeve being secured to the cover 8 by means of studs 14 which also secure a bearing cap 15 containing a roller bearing 17 in which rotates a shaft 20. At each end of the sleeve 10 is an aperture disc 16, the apertures 18 of which are surrounded by beads 22. Each bead is engaged by a suitable seal 24 which lies in sealing engagement about a tubular extension 26 of the shaft 20. Between the seals 24 is a spring 28 which presses the seals against the beads 22. The tubular extension 26 of the shaft 20, between the two seals 24 is provided with air inlet apertures 30 permitting air through the intake 12 to flow downwardly through the tubular extension 26.

On the end of the tubular extension 26 is a cylinder head 32 secured by studs 34 to a cylinder block, generally indicated at 36. The cylinder head 32 can be pressed, keyed or otherwise secured on the lower end 20 of the tubular extension 26 of shaft 20.

The cylinder block 36 comprises a set of four cylinders 38 connected by a central web 40 and closed at their upper ends by the cylinder head 32. Above the central web 40 is an upstanding circular wall 42 which connects the cylinders 38 and which with the central portion of the cylinder head 32 provides an inlet manifold 44 which is in flow communication with the upper portions of the cylinders 38 by means of intake slots 46.

In each cylinder 38 is a piston 48 having working faces 50 directed upwardly in the cylinder. Above each piston 48 and in each cylinder 38 is a pair of one-way exhaust valves 52 which provides flow of compressed air or other gases from the cylinders 38 to the interior 54 of the housing 6, which comprises a pressure chamber. This chamber has an outlet 55 for the outward flow of pressurized gases for such work as the occasion may require.

The pistons 48 have lower end portions 56 which lie at an angle to the longitudinal axis of the piston. These angled end portions 56 are provided with enlarged portions 58 having flat end pressure faces 60. It should be noted that the pistons 48 are freely rotatable in the cylinders 38.

The housing 6 has a bottom 62 with a central opening 64 giving access to a stud 66 extending through a base member 68 and threaded into a bearing support 70 whose upper portion is cup-shaped and supports a tapered thrust-bearing assembly 72 in which is a stub shaft 74 located in the underside of the web 40 which connects the cylinders 38 of the cylinder block 36. Rotation of the shaft 20 causes rotation of the cylinder head 32 and cylinder block 36 as a unit by means of the mounting of the cylinder head on the tubular extension 26 of the shaft 20.

Rotatable on the bearing support 70 is a spider 76 having U-shaped cutouts 78 in which lie the angularly disposed lower ends 56 of the pistons 48. The spider 76 overlies the enlarged or flanged ends 58 at the bottom of the pistons and said spider holds the piston ends 58 in engagement with a cam plate 80 which has a hub flange 82 mounted upon an inwardly concentric flange 84 which extends upwardly from the support 68. The

flange 82 of the cam plate 80 is movable on the supporting flange 82 and a spring 86 between the support 68 and the underside of the cam plate 80 compresses the cam plate against the pressure face 60 of each piston and also exerts yielding pressure against the spider 76 and a thrust bearing comprising a ball bearing assembly 88.

As the shaft 20 is rotated by any suitable means, such as an electric motor or a gasoline engine, the cylinder block 36 is rotated and with the cam plate 80 lying on a plane oblique to the longitudinal axis of the pistons and the shaft 20, the pistons will be caused to ride up to the high side of the cam, pushing the pistons upwardly into the cylinders through a compression stroke. Then the pistons ride down to the low side of the cam, drawing the pistons downwardly in an intake stroke, one circuit of the cam plate by a piston comprising one complete cycle. Intake air of course is drawn through the intake 12 down through the tubular extension 26 of the shaft 20 into the intake manifold 44 and thence through intake ports 46 to the interiors of the cylinders 38. As the piston rises in the cylinders they pass the intake ports 46 and compress air or other gases on further movement of the piston to the top of the stroke, as indicated on the left side of FIG. 2. These compressed gases are forced through the valves 52 into the pressure reservoir or chamber 54 where the pressure air is accumulated and from which it can lead to the pressure outlet 55 to a suitable device for performing work.

The cam plate 80 is provided with a circular cutout 90 which extends about the cam plate from the low point of said plate to the high point thereof, the relative movement of the pistons during the compression stroke being from the low point to the high point and substantially coextensive with the length of said semicircular cutout 90. The pressure faces 60 of the pistons 48 are normally in sealing sliding contact with the flat smooth surface of the cam plate 80 so that pressure in the pressure chamber 54 is sealed from the piston pressure faces. However, when the pistons begin their compression stroke from the low side to the high side of the cam plate 80, the semicircular cutout portion 90 exposes most of the surface of the pressure face 60 of the piston so that pressure is exerted on the under end of the piston to tend to force it upwardly into the cylinder, working with the obliquely positioned surface of the cam plate 80 to force the piston upwardly during said compression stroke. Then when a piston reaches the top of the cam at the left side of FIG. 2, the upper end of the semicircular cutout 90, defined by the edge 92 in FIG. 5, wipes across the pressure face 60 of the piston and brings said pressure face back into smooth sliding and sealing contact with the upper face of the cam plate 80, much in the manner of placing two Johansson gage blocks together with a sliding movement.

FIG. 4 is a diagrammatic illustration of one of the pistons 48 in a cylinder 38. The piston 48 at position A would be in the same position as that shown at the right side of FIG. 2. As the cylinder block and piston assembly are rotated as a unit, the piston 48 rides up the cam in the compression stroke. Position B would be the position of the piston midway between the low and high sides of the cam. Position C illustrates the top of the compression stroke. Position D shows the same piston half way down from the high to the low side of the cam

and position A' is the same position as position A at the completion of a cycle.

From the foregoing it will be seen that there is provided a compressor construction wherein the gases which have been compressed are utilized to assist in the compression stroke of each of the pistons, rather than oppose the compression and exhaustion of compressed gases as in conventional types of compressors. Because the accumulated pressure is put to work, much less power is required from the prime mover which operates the compressor. Not only does this construction result in a considerable reduction in the amount of power required but it provides a smooth operating unit which does not have the objectionable vibration of the single piston compressors of the usual type. This is a particular advantage in automobile air conditioning systems but of course is useful in other environments.

The device can be made in any desired sizes. However, it should be noted that for use in restricted spaces it can be made quite small yet because of its multiple cylinder arrangement, will produce quite ample supplies of gases under pressure in a given time.

It should be noted that various changes can be made in the form, details, arrangement and proportions of the various parts without departing from the spirit of the invention.

I claim:

1. A compressor or the like including a cylinder having an inlet and an outlet and a reciprocating piston, in one position thereof, having a portion located and working in the cylinder between the inlet and outlet and movable through a cycle having an intake stroke and a compression stroke, wherein the improvement comprises: a pressure chamber in flow communication with the cylinder outlet, the piston having a working face in the cylinder to pressurize gases therein during the compression stroke, said piston having a pressure face opposed to the working face, means for exposing the pressure face to pressure in said pressure chamber during the compression stroke of the piston and for isolating said pressure face from pressures in the pressure chamber during the intake stroke of the piston.

2. The structure in claim 1, and the pressure face of said piston being located exteriorly of the cylinder and interiorly of the pressure chamber.

3. The structure in claim 1, and the cylinder and piston being located within the pressure chamber, and the inlet of said cylinder extending exteriorly of and being sealed from the pressure chamber.

4. The structure in claim 1, and a cam engaging said piston, and means for providing relative movement of the cam and piston to reciprocate the piston.

5. The structure in claim 1, and said means for subjecting the pressure face of the piston to pressures in the pressure chamber comprising a cam having face-to-face wiping contact with said pressure face and also having a portion thereof arranged to cyclically expose said pressure face to the pressures in said pressure chamber.

6. The structure in claim 5, and said cam comprising a member having a flat face in a plane oblique to the path of reception of said piston, the pressure face of the piston being flat and flatly engaging the face of the cam in freely slidable relation thereto and sealed from pressure chamber pressures, means associated with said piston for holding the flat pressure face thereof in engagement with the flat face of the cam, and said cam having

a relieved portion in pressure communication with said pressure chamber and cyclically registerable with the flat pressure face of the piston to exert pressure against said pressure face upon relative movement between the cam and the piston.

7. The structure in claim 5, and said cam comprising a plate having a flat surface of revolution in wiping contact with the pressure face of the piston, said plate having a semicircular relieved portion exposing the pressure face of the piston to pressure chamber pressures during the compression stroke of the cycle of the piston.

8. The structure in claim 5, and said cam comprising

a plate having a flat surface of revolution in wiping contact with the pressure face of the piston, said plate having a semicircular relieved portion exposing the pressure face of the piston to pressure chamber pressures during the compression stroke of the cycle of the piston.

9. The structure in claim 1, and the pressure face of the piston lying on a plane oblique to that of the longitudinal axis of the piston, the piston being rotatable in the cylinder, and a cam plate in wiping contact with said pressure face and on a plane coincident with that of the pressure face.
